UNITED STATES PATENT OFFICE.

WILLIAM T. BRANNAN, OF ELDRED, ILLINOIS.

CHAIN FASTENER.

Application filed August 2, 1924. Serial No. 729,735.

To all whom it may concern:

Be it known that I, WILLIAM T. BRANNAN, a citizen of the United States, residing at Eldred, in the county of Greene and 5 State of Illinois, have invented certain new and useful Improvements in Chain Fasteners, of which the following is a specification, reference being had to the accompanying drawings.

10 This invention relates to chain fasteners and has for an important object thereof the provision of a chain fastener, for use with automobile chains, which is firmly latched when in the closed position.

15 A further object of the invention is to provide a device of this character in which movements of the plates to closed position is limited at such a point that the movable plate, which forms the closure for the chain 20 receiving cove of the stationary plate, is so positioned that the strain of the chain secured by the fastener is placed upon this movable plate and tends to shift the same further into the closed position, such further 25 movement being limited by a suitable stop.

A still further object of the invention is to provide a device of this character which may be very cheaply and readily produced, which will be durable and efficient in 30 service and a general improvement in the art.

These and other objects I attain by the construction shown in the accompanying drawings, wherein for the purpose of illustration is shown a preferred embodiment of 35 my invention and wherein:—

Figure 1 is a side elevation of a chain fastener constructed in accordance with my invention;

40 Figure 2 is a longitudinal sectional view therethrough;

Figure 3 is a plan view thereof;

Figure 4 is a transverse sectional view taken therethrough showing the construction 45 of the catch.

Referring now more particularly to the drawings, the numerals 10 and 11 indicate stationary and movable sections of the chain fastener, the stationary section being 50 adapted for connection with one end link of the side chains of an automobile anti-skid chain, as indicated at 12. The stationary member preferably consists of two similar plates 10^a and 10^b, although the

55 plate 10^b can be omitted as is found desirable. Adjacent that end remote from the

fastener 12 by means of which the anti-skid chain is attached, the stationary section has formed through its side edge a notch 13 extending slightly more than half-way across 60 the plate, as shown, and terminating at its lower end in a chain receiving cove 14. At a point centrally of the plate and between this notch and the adjacent end of the stationary section, the movable section 11 is 65 pivoted to the stationary section, as at 15.

This movable section has formed therein a chain link receiving notch 16, the notch being so formed and so associated with the pivot 15 that it forms of the movable section a lever having a short arm 17 and a long arm 18. The terminal of the long section is formed to provide a hook 19, the outer surface of which is provided with corrugations 20. This extremity during 70 swinging of the movable section to the closed position, where it lies between the plates 10^a and 10^b of the stationary section, comes into contact with a spacing element 21 arranged between the plates about the 75 connection 12 to limit movement of the movable section to the closed position.

When at the limit of its movement the movable section, and more particularly that portion thereof lying between the base of the 80 notch 16 and the opposite edge of the long section 18 of the lever, lies across the mouth of the notch 13 to close the same preventing the escape of a chain link therefrom. The face 22 of the short arm of the lever at this 85 time lies between the fastening 12 and the remote wall of the cove 14 so that strain placed upon a chain link 23 engaged in this cove, which is applied in a direction away from the connection 12, will tend to rotate the 90 movable section toward the spacer 21 and maintain the engagement between the free end of the movable section and this separator thereby preventing accidental opening 95 of the fastener. When in this position the hook 19 extends beyond the end of the stationary section so as to permit the engagement of a screw-driver or the like in the eye 24 thereof or to permit engagement of the hook proper with a pair of pliers or 100 the like to open the fastener.

As a still further precaution against accidental opening of the fastener when in applied position, one of the sections is provided with a resilient tongue 25 having its 110 free end lying in the path of the other of the sections. In the present instance this

tongue is shown as formed on the section 10 by slotting the plate 10^a, as at 26, and adjacent the notch 13 so that the tongue is formed between the slot and notch. The 5 other of the sections is provided with a notch 27 receiving the hooked terminal 28 of this tongue when the sections are in the closed position, and that edge thereof opposing the hooked end 28 of the tongue 25 as the 10 sections are moved to closed position is cam faced, as at 29, to cam the hooked extension over and cause it to slide against the side face of the section for delivery into the notch 27. It will be obvious that when in 15 the closed position this tongue by its engagement in the notch will latch the sections firmly in the closed position and render accidental separation thereof practically impossible.

20 Many changes being possible in the construction hereinbefore set forth without materially departing from the spirit of my invention, I do not limit myself to such specific structure except as hereinafter claimed.

25 I claim:—

1. A chain fastener comprising a pair of plates pivotally connected adjacent their ends to swing in parallel planes to extended or side to side relation, one of said plates 30 having a notch in its side terminating in a chain receiving cove, the other of the plates having a chain link receiving notch delivering an engaged link into the cove of the first named plate, means limiting the movement 35 of the movable plate, and means limiting the movement of the last named plate into side

to side relation with the first named plate with a wall of the notch extending into the cove, one of said plates having in its side wall a notch, the other of the plates having 40 a resilient tongue provided with a hooked end extending into the path of movement of the plate having the notch, the notch bearing plate having the wall thereof opposing said hooked end during movement of the 45 plates to side to side relation cam faced to deliver said hooked end to the side face thereof having the notch.

2. A chain fastener comprising a pair of plates pivotally connected adjacent their 50 ends to swing in parallel planes to extended or side to side relation, one of said plates having a notch in its side terminating in a chain receiving cove, the other of the plates having a chain link receiving notch delivering 55 an engaged link into the cove of the first named plate, means limiting the movement of the movable plate, and means limiting the movement of the last named plate into side to side relation with the first 60 named plate with a wall of the notch extending into the cove, the first named plate being permanently attached to one end of the chain at the end thereof remote from that having the notch, the other of the plates 65 having a hooked free end extending beyond the chain attached end of the first named plate when the plates are in side to side relation.

In testimony whereof I hereunto affix my 70 signature.

WILLIAM T. BRANNAN.
